FIG. 1

FIG. 2

FIG. 4

FIG. 3

To all whom it may concern:

Be it known that I, Dean Evans Larson, a citizen of the United States, residing at Denver, in the county of Denver and State of Colorado, have invented a new, original, and ornamental Design for a Golf Tee, of which the following is a specification, reference being had to the accompanying drawing, forming a part hereof.

Figure 1 is a side elevational view of a golf tee, showing my new design;

Figure 2 is a side elevational view thereof with the tee rotated 45 degrees from the position shown in Figure 1;

Figure 3 is a bottom plan view thereof; and

Figure 4 is a top perspective view, looking at the side shown in Figure 2.

The tee is symmetrical around a vertical axis. The broken lines indicating advertising printing in Figure 4 are for illustrative purposes only.

I claim:

The ornamental design for a golf tee, as shown and described.
